UNITED STATES PATENT OFFICE

161,598

KNOCKDOWN HANGING SHELF

Paul A. Sheets, Santa Monica, Calif.

Application January 6, 1950, Serial No. 7,041

Term of patent 3½ years

(Cl. D33—3)

To all whom it may concern:

Be it known that I, Paul A. Sheets, a citizen of the United States and a resident of Santa Monica, in the county of Los Angeles and State of California, have invented a new, original, and ornamental Design for a Knockdown Hanging Shelf, of which the following is a specification, reference being had to the accompanying drawings, forming a part thereof.

I claim:

The ornamental design for a knockdown hanging shelf, substantially as shown.

PAUL A. SHEETS.
